UNITED STATES PATENT OFFICE.

CHARLES FRANCIS PHILLIPS, OF BLACKHEATH, LONDON, ENGLAND.

ELECTRICAL TRANSFORMER.

Application filed February 24, 1928, Serial No. 256,748, and in Great Britain October 18, 1926.

This invention relates to electrical transformers and particularly low frequency transformers used in wireless transmitting and receiving apparatus.

5 In small transformers of the type customarily used for low frequency coupling between thermionic valves it is well known that the primary winding is very subject to breakdown. It is generally assumed that the breakdown is due either to vibration of the wire or to too great current density. Investigations I have made have proved however, that breakdown is due in most cases to electrolysis. As ordinarily connected in 10 wireless receiving sets or amplifiers the primary winding of the transformer is usually connected to the positive pole of the high tension battery while the secondary winding is usually connected to the negative pole 15 of that battery either directly or through the battery used for heating the valve filaments. Assuming a high insulation resistance between these primary and secondary windings it is clear that during the operation of the 20 amplifier and also usually while the amplifier is not in use, the full potential of the high tension battery will be applied to the high insulation resistance between primary and secondary of the transformer and that 25 a very small current will flow between them.

Owing to the impossibility in actual manufacture of entirely excluding moisture from the material separating the coils, and further owing to the fact it is commercially impracticable to obtain insulated wire entirely free from minute pinholes in the insulation, it is clear that I have a condition in which electrolysis is possible, and that as the primary winding may be regarded as the 30 anode that winding will be destroyed by the electrolytic action at the point at which the current leaves the winding.

Considering the insulation between the coils, it is obvious that there are two paths 45 through the insulation resistance, one being a direct path from coil to coil and the other a path from the primary coil to the metal core, and from the core back to the secondary coil.

50 It is impossible in practice so to insulate the windings as to render electrolyzing leakage currents impossible, and my invention consists broadly in providing means whereby the leakage currents leaving the higher 55 potential winding leave entirely by a metallic path which I term an electrolytic

shield and which is sufficiently substantial to withstand electrolytic action.

In order that the invention may be the more clearly understood a number of inter-valve transformers in accordance therewith will now be described reference being made to the accompanying diagrammatical drawings, Figures 1, 2 and 3, which illustrate respectively three of said transformers.

60 Thus in Figure 1 is illustrated a transformer comprising an iron core 1 a primary winding 2 and a secondary winding 3. In this case the electrolytic shield is constituted partly by a winding 4 located between the two transformer windings and partly by the iron core 1. The winding 4 may be nothing more than a continuation of the primary winding 2 which may be wound in the usual way in layers with insulating material between. Said winding 4 is however preferably of heavier gauge wire than that used for the primary itself.

65 The terminal P of the winding 2 is frequently adapted to be connected to the plate of a valve while the terminal marked + is adapted to be connected to the high tension positive. The winding 4 and the core 1 are therefore both connected to said winding 2 at its end which is connected to said terminal +. The letter G and the sign - respectively designate the terminals of the secondary winding which are usually adapted to be connected to the grid and the high tension negative.

70 The transformer illustrated in Figure 2 differs from that of Figure 1 in that a non-magnetic metallic cylinder 4^a, split to prevent the generation of eddy currents, takes the place of the coil 4. In this figure moreover the transformer windings are shown as made up of sections connected in series being wound, say, in a multi slot moulding in the well known way.

75 The transformer of Figure 3 differs from that of Figure 2 in that the sections of the primary winding instead of being wound in a multi slot former are wound on separate metal or metallized bobbins 4^b having side cheeks as indicated which bobbins take the 80 place of the cylinder 4^a. These bobbins are insulated from one another and serve to connect the several sections of the primary winding as clearly shown in the drawing. Like the cylinder 4^a of Figure 2 these bobbins 85 are split across to prevent the generation of eddy currents. It will be clear that these 90

95 100 105 110

bobbins while forming the necessary electrolytic shield, are so connected that the bobbins are of a progressively varying potential and thus the inherent capacity of the winding 5 remains small.

In each example described the secondary has been shown inside and the primary outside. This arrangement may of course be reversed or I may use a split secondary with 10 the primary in between. In this latter case the shield will of course have to have a part both inside and outside of the primary.

Further, in each of the examples described the core of the transformer has been described as connected to high tension positive 15 so that said core forms part of the electrolytic shield. This of course is not essential and is only desirable in cases where it is reasonably probable that the electrolyzing 20 current might otherwise pass from the primary winding to the secondary winding by way of the core.

I am aware that electrical transformers have been heretofore proposed having an electrostatic shield located between the primary and secondary windings and connected to one end of the latter. 25

What I claim and desire to secure by Letters Patent is:—

In an electrical transformer for use in 30 radio receiving or transmitting apparatus with its primary winding connected to the positive, and its secondary winding to the negative pole of the high tension battery, an electrolytic shield connected to said primary 35 winding, said primary winding being wound in sections, each section being surrounded on its sides adjacent other sections and adjacent the secondary by a section of the said shield, said shield sections being each connected to 40 a section of the primary.

In witness whereof I affix my signature.

CHARLES FRANCIS PHILLIPS.
